UNITED STATES PATENT OFFICE.

KNUT KLEVEN, OF MOUNT HOORB, WISCONSIN.

SILO-DOOR FASTENER.

No. 921,122.

Specification of Letters Patent.

Patented May 11, 1909.

Application filed July 1, 1908. Serial No. 441,377.

To all whom it may concern:

Be it known that I, KNUT KLEVEN, a citizen of the United States, residing at Mount Horeb, in the county of Dane and State of Wisconsin, have invented a new and useful 5 Silo-Door Fastener, of which the following is a specification.

This invention relates to silos of that general class shown and described in my former 10 application for patent filed in the United States Patent Office on the 11th day of April 1908 under Serial No. 426501.

The object of the invention is generally to improve and simplify the construction of the 15 silo and to provide improved means for locking the removable door sections in closed position.

A further object of the invention is to so 20 arrange the locking members that the inner ends of the same are entirely housed within the door sections, thereby to present a smooth unobstructed surface to the ensilage and permit the latter to settle when filling the silo.

25 A further object is to reinforce and strengthen the several door sections by the provision of transverse rods or bars which form in effect a ladder so that a person may ascend or descend the silo.

30 A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

40 In the accompanying drawings forming a part of this specification:—Figure 1 is a front elevation of a silo constructed in accordance with my invention. Fig. 2 is a vertical sectional view of a portion of the silo. Fig. 3 is 45 a transverse sectional view taken on the line 3—3 of Fig. 2. Fig. 4 is a top plan view of one of the door sections detached. Fig. 5 is a detail perspective view of one of the fastening devices detached.

50 Similar numerals of reference indicate corresponding parts in all of the figures of the drawings.

The improved silo forming the subject matter of the present invention includes a 55 body portion 5 preferably formed of vertical

staves arranged in cylindrical form, as shown, some of the staves being spaced apart to produce a continuous door way 6, preferably extending the entire height of the silo.

Arranged within the door way is a frame 60 including longitudinal side members 7 spaced apart by transverse bars 8, which latter form supports for the removable door sections, indicated at 9. The door sections 9 are each preferably formed of superposed transverse 65 strips having their outer faces reinforced and strengthened by vertical cleats or bars 10, the latter being bowed outwardly and connected with the adjacent door section by means of bolts or similar fastening devices 70 11 and 12.

Connecting the cleats or bars of the several door sections are transverse rods 13 having their opposite ends flattened and provided with perforations for the reception of the 75 bolts 11, said rods forming in effect a ladder so that a person may readily ascend or descend the silo. The inner face of each door section is inclined or beveled at 14 for engagement with the correspondingly inclined 80 face of the door frame 7 so that the door will snugly engage the interior wall of the silo and thus prevent the escape of fodder from the latter. The opposite ends of the longitudinal cleats 10 preferably terminate short of 85 the adjacent transverse edges of the door sections to form stops 15 for engagement with the adjacent transverse bars 8 of the door frame, thereby to assist in supporting the door sections within said frame. The 90 upper transverse edge of each door section is formed with spaced recesses in which are seated castings or sockets 16 adapted to receive suitable locking pins 17 carried by the lower edge of the adjacent door section, 95 whereby the several sections may be locked in vertical alignment with each other.

Extending through the transverse bars 8 are spaced locking bolts 18 having their outer ends threaded and their inner ends provided with terminal eyes 19 adapted to receive the free ends of the locking pins 17. Engaging the threaded ends of the bolts 18 are clamping nuts 20 each provided with a handle or lever 21 by means of which the 105 nuts may be rotated so as to cause the walls of the eyes 19 to engage the pins 17 and thus securely lock the door sections in closed position. Attention is here called to the fact that the locking members 18 are disposed at 110

the juncture of adjacent door sections, while the eyes 19 of said locking members are seated in suitable recesses 22 formed in said door sections, whereby the inner ends of the locking members are entirely housed within the door sections so as to present a smooth unobstructed surface to the ensilage or other fodder and thus permit settling of the latter when filling the silo. The silo is reinforced 10 and strengthened by the provision of one or more hoops or bands 23, which latter bear against the transverse bars 8 of the door frame and are provided with the usual turn buckles by means of which the tension of the 15 hoops may be adjusted. It will thus be seen that by releasing the clamping nuts 20 of one door section the next succeeding door section may be readily removed by imparting a slight upward movement to said door section which disengages the terminals of the pins 17 from the socket 16 and eyes 19 thus permitting the door section to be detached.

In order to lock the door in closed position it is merely necessary to insert the terminals 25 of the pins 17 through the eyes 19 into the adjacent sockets 16 and then rotate the clamping nuts 20, the clamping action exerted by the eyes of the members 18 on the pin 17 serving to securely lock the door 30 against accidental displacement. By extending the door way the entire height of the silo and forming the closure for the doorway in sections, access may be had to the interior of the silo at any desired height, the doorway 35 and door sections being so constructed as to afford little or no obstruction to the passage of fodder in filling or emptying the silo. Attention is here called to the fact that the inner faces of the several door sections present a 40 smooth unobstructed surface to the fodder throughout the height of the silo, while the transverse rods 13 form in effect a ladder by means of which a person may readily ascend the silo to manipulate the clamping nuts 45 when releasing the door sections or securing said door sections in closed position.

From the foregoing description it is thought that the construction and operation of the device will be readily understood by those 50 skilled in the art and further description thereof is deemed unnecessary.

Having thus described the invention what is claimed is:

1. A silo having a door way, a continuous 55 series of individual door sections closing the door way, and fastening devices disposed at the meeting edges of adjacent door sections and forming a locking means for the door sections, the inner ends of the fastening devices being entirely housed within the door sections.

2. A silo having a door way, a continuous 60 series of individual door sections closing the door way and having their meeting faces provided with interlocking parts, and fastening

devices engaging the interlocking parts of the door sections for securing said door sections in closed position.

3. A silo having a door way, a continuous series of individual door sections closing the 70 door way, bolts interposed between the meeting edges of adjacent door sections and provided with terminal eyes entirely housed within said door sections, and locking members secured to the lower edge of each door 75 section and passing through the eyes of the adjacent bolts for engagement with the upper edge of the next succeeding door section.

4. A silo having a door way, a continuous series of individual door sections closing the 80 door way and each having its upper edge provided with a socket, a locking pin secured to the lower edge of each door section and adapted to enter the adjacent socket, and a fastening device disposed at the meeting 85 edges of adjacent door sections for engagement with the pins.

5. A silo having a door way, a continuous series of individual door sections closing the door way, threaded bolts interposed between 90 the meeting edges of adjacent door sections and provided with terminal eyes, there being sockets formed in the upper edge of each door section, pins depending from the lower end of each door section and extending through 95 the adjacent eyes for engagement with the sockets, and clamping nuts threaded on the bolts for clamping the eyes in engagement with the pins, said pins and eyes being entirely housed within the door sections.

6. A silo having a door way, a frame seated in the door way and provided with transverse bars, a series of individual door sections fitting between the transverse bars and each provided with spaced longitudinal cleats terminating short of the opposite ends of the door section to form stops for engagement with the transverse bars, rods connecting the cleats, and fastening devices disposed at the meeting edges of adjacent door sections and forming a locking means for the door sections, the inner ends of the fastening devices being entirely housed within the door sections.

7. A silo having a door way, a frame seated 115 in the door way and provided with spaced transverse bars, a series of individual door sections fitting between the transverse bars and having their outer faces inclined for engagement with the inner face of the door frame, there being sockets in the upper edge 120 of each door section, pins depending from the lower edge of each door section and adapted to enter the adjacent sockets, and clamping bolts extending through the transverse bars 125 of the frame and engaging the adjacent depending locking pins.

8. A silo having a door way, a frame seated in the door way and provided with spaced transverse bars, a series of individual door 130

sections fitting between the transverse bars, and having their upper edges provided with sockets, locking pins depending from the lower edge of each door section and adapted to enter the adjacent sockets, spaced outwardly bowed longitudinal cleats secured to the exterior face of each door section, transverse rods connecting the cleats of each door section and having their opposite ends provided with perforations, fastening devices extending through the perforations and the adjacent longitudinal cleats, threaded bolts piercing the transverse bars and provided with terminal eyes for engagement with the

adjacent locking pins, there being recesses 15 formed in the several door sections at said pins for the reception of the eyes, and clamping nuts engaging the threaded ends of the bolts for clamping the eyes in engagement with said pins. 20

In testimony that I claim the foregoing as my own, I have hereto affixed my signature in the presence of two witnesses.

KNUT KLEVEN.
